UNITED STATES PATENT OFFICE.

JOSEPH STEVENS McCABE, OF MINNEAPOLIS, MINNESOTA.

CONCRETE-CULVERT MOLD.

1,275,280.

Specification of Letters Patent. Patented Aug. 13, 1918.

Application filed December 19, 1917. Serial No. 207,872.

To all whom it may concern:

Be it known that I, JOSEPH S. McCABE, a citizen of the United States, and a resident of Minneapolis, in the county of Hennepin 5 and State of Minnesota, have invented a new and useful Improvement in Concrete-Culvert Molds, of which the following is a specification.

My present invention relates generally to 10 concrete culvert molds, and more particularly to that type of mold shown and described in the Patent No. 1243910 granted to me as assignee of Henry F. Worley, under date of October 23, 1917, the objects of my 15 present invention being the improvement of certain parts of the apparatus described and claimed in said patent, in the interest of strength and durability.

More specifically, my present invention 20 aims to improve the supporting arches of the patent above referred to, in certain respects the details of which will be presently brought out, another object being the provision of mold plates of improved constructions so as to render them stronger and more durable.

In the accompanying drawings illustrating my present improvement:

Figure 1 is a transverse sectional view 30 through the parts effected by my present invention, illustrating one of the supporting arches in elevation.

Fig. 2 is a detail perspective view of a portion of one of the mold plates, and

Fig. 3 is a similar view of one of the crown plates.

Referring now to these figures, I have indicated generally at 10 one of the supporting arches, of which any suitable number 40 may be utilized, and which are supported in upright operative position in use, by any suitable means, as for instance the means shown in the patent above referred to, and unaffected by my present improvement.

Each of the supporting arches 10 is formed by bending a section of angle iron to substantially a semi-circular form, and in the patent above referred to, the outstanding flange of the angle iron is notched to receive the flanged portion of the mold plate.

My present improvements propose the elimination of these notches in the outstanding flange of the supporting arch, for the reason that they are likely to weaken the same and greatly reduce its stability, and my improvements propose to substitute therefor,

a plurality of radiating lugs 11, disposed flatwise against the outstanding flange 12 of the arch, with inner butt portions engaging the outer face of the lateral flange 13 of the arch, so that in order to rigidly secure the several lugs in place, a single connecting bolt 14 extending through the same and through the arched flange 12, is sufficient.

The outer portions of the several lugs 11 have up-standing hooks 15 which engage the flanged portions of the several mold plates 16, which latter extend in their length between two or more of the supporting arches 10 and have portions lapping one another circumferentially of the arches.

Each of the mold plates 16 has an angular flange 17 along one edge, and this angular flange 17 is, in accordance with my present invention, provided with an extension 18 bent inwardly along a portion of the inner face of the flange 17 for a portion of the length of the said extension, the latter being bent angularly at 19 across the angle between the plate 16 and its flange 17 and having its free edge 20 paralleling a portion of the said mold plate 16. The opposite or free edge of the mold plate is turned inwardly thereon, as indicated at 21 and seen particularly in Figs. 1 and 2, so that the two edges are thus reinforced, the flanged end 17 being more heavily reinforced by virtue of the fact that it is this portion of the mold plate which is engaged by the outer hooked end of the respective lug 11.

It is obvious that the portion of the extension 18 paralleling the flange 17 reinforces the latter, while the portion 19 of the extension 18, in consideration of the fact that its edge 20 parallels a portion of the plate 16, forms an effective brace for the angle between the plate 16 and its flange 17.

As seen in Fig. 1, the several mold plates are utilized in lapped relation from both ends of the arch 10 toward the upper central portion of the latter, the remaining space at the upper central portion of the arch being occupied by a crown plate 22, which latter is in accordance with my invention, provided with extensions at its opposite edges, portions of which parallel its inner side faces as indicated at 23 in Fig. 3, and portions 24 of which are bent inwardly at angles, so that the side portions of the crown plate 22, that is those portions which lap portions of the adjacent mold plates 16

at opposite sides thereof, are effectively braced and rendered stronger and more durable in much the same way as the mold plates 16.

5. I claim:

1. A concrete culvert mold including supporting arches formed of curved angle bars, a plurality of lugs carried thereby, each of said lugs being secured to the outstanding 10 flange of the arch and having an inner enlarged end abutting the lateral flange of the arch and being provided with a hook projecting beyond the arch, and a plurality of flanged mold plates, the flanges of which are 15 engaged by the outer hooks of the several supporting lugs.
2. A concrete culvert mold including supporting arches and mold plates supported by the arches, each of said mold plates having an angular flange along one edge provided with an extension, the latter being bent inwardly toward the inner face of the mold plate and having portions paralleling the inner face of the flange and the mold 20 plate, for the purpose described.
- 25

Copies of this patent may be obtained for five cents each, by addressing the "Commissioner of Patents, Washington, D. C."

3. A concrete culvert mold comprising supporting arches, and a plurality of mold plates supported by the arches, each of said mold plates having an angular flange along one edge thereof provided with a reverting 30 extension, said extension having portions paralleling the inner face of the flange and the inner face of the mold plate and having a portion extending across the angle between the mold plate and its flange, for the purpose 35 described.

4. A concrete culvert mold comprising supporting arches, a plurality of mold plates supported by the arches, and a crown plate lapping certain of the mold plates and having its side edges provided with extensions bent inwardly and at an angle to the plates, 40 said extensions having certain portions which parallel one another, and other portions which parallel the inner lower face of 45 the crown plate, for the purpose described.

JOSEPH STEVENS McCABE.
